UNITED STATES PATENT OFFICE.

VINCENT L. JONES, OF NEW HAVEN, CONNECTICUT.

BOILER.

Application filed July 26, 1923. Serial No. 653,922.

This invention relates to steam generators of the type embodying water tubes set side by side and the particular purpose is to provide for the assembly and combination of a number of such tubes in the generator in such a manner that they will be easy of access for cleaning, replacement and repair and in particular to provide a structure whereby a suitable opening may be provided through the assembly of tubes.

As examples of such an opening as I have referred to I may mention the fire door and openings for the application of mechanical stokers to the back wall of a locomotive firebox of the water tube type and by way of example I have here illustrated a construction providing for the application of mechanical stokers to such a firebox.

My invention will be readily understood by reference to the following description of the illustrative embodiment thereof taken in connection with the accompanying drawings, wherein:

Fig. 1 is a rear end elevation of a locomotive firebox;

Fig. 2 is a vertical longitudinal section through the rear portion of the firebox substantially on the line 2—2 of Fig. 1; and

Fig. 3 is a section on the line 3—3 of Fig. 1.

Referring to the drawings, I have there illustrated a form of locomotive boiler of the general type disclosed in the patent to James M. McClellon 1,248,356, Nov. 27, 1917, and embodying a firebox having a foundation chamber 3 and a crown chamber 5 connected by side walls of tubes 7 set side by side substantially in contact and communicating with the crown chamber and the foundation chamber the construction of the side walls being substantially as disclosed in the patent referred to. I have here illustrated the foundation chamber 3 as in the form of a hollow steel casting of generally circular section but having flat ridges 8 at the top and bottom, the former being formed with openings in which the tubes 7 and the tubes of the rear wall later to be referred to are rolled and beaded and the latter providing for the application of plugs 9 opposite the ends of said tubes. The flat ridges 8 are conveniently formed in the casting operation at the proper inclination to facilitate the assembly of the parts.

The crown chamber 5 may be of the general type disclosed in the patent referred to

and comprise a central cylindrical drum 11 and lateral drums 13, the drums having flattened contacting surfaces and the center drum 11 seating between the lateral drums 60 in the manner of a keystone. The portions of the drums which are not in contact are of cylindrical pressure-resisting form and preferably the drums preserve this form throughout their length. The rear ends 65 thereof may be closed by heads 15 and the front ends, which are left open, may pass through a suitable flanged opening in the tube sheet 17 and be riveted to the flanges 19 of the latter. Preferably as shown the three 70 drums occupy positions substantially tangent to the interior of the barrel shell 21, which latter may be provided, as disclosed in the McClellon patent referred to, with a lower segmental extension 23 defining a combustion chamber and secured at 25 to the sides of the lateral drums and contributing to the support of the crown chamber.

The rear wall of the boiler may comprise a series of water tubes 27 and 27^a preferably 80 of uniform diameter. The tubes 27 and 27^a enter the foundation chamber 3 and the crown drums and have their ends rolled and beaded on the interior of the same. Since the tubes are of uniform diameter they may be readily given a suitable curvature as shown so that their ends may be presented normally, that is, perpendicularly, to the parts with which they are connected. The space between the tubes is closed at the rear 90 of the firebox by suitable nonconducting material such as fire brick (not shown). This construction is practicable particularly since the rear wall of the firebox is not subjected to such high heats as the side walls 95 and since the walls of large tubes 7 at the side of the firebox provide for the circulation of an effective volume of water and for a large heating surface. The reduction in area of the heating surface which might 100 be expected from the smaller size of the rear wall tubes may be somewhat compensated for by so applying the refractory material as to leave a relatively large portion of the circumferences of the tubes exposed.

The rear wall of the firebox may be provided with a suitable fire door opening 29 and with suitable openings 31 providing for the application of mechanical stoking devices. The invention claimed herein more particularly relates to the construction 110 which provides for these openings 31. I

have not here attempted to show the mechanical stoker as it in itself forms no part of my invention but the construction illustrated is one designed for use with a so-called "Duplex" stoker, for further disclosure of which I refer to the "Locomotive Cyclopedia" (New York), 6th edition, 1922, pages 397 to 402.

The opening 31 in the form of my invention illustrated is defined by a suitable frame-like hollow header 32 conveniently formed of a single integral casting and providing, as clearly shown by Figs. 2 and 3, a water chamber 33 completely surrounding the opening. This water chamber communicates with the crown chamber and with the foundation chamber 3 by means of tubes 27^a forming a portion of the rear wall. The opening 31 is conveniently formed with a flange 35 exposed at the exterior of the firebox against which the stoker mechanism may seat.

The tubes 27 and 27^a considered as a whole provide a rear wall for the firebox and in a sense may be referred to as coplanar tubes although this word obviously is not used in the strict geometrical sense of the word "plane". The significance, however, will be clear. The frame-like header 32 which provides for the application of a stoker is disposed in and forms a portion of this wall. An important feature of my invention provides for the connection of the tubes 27^a to this header and in a manner providing for convenient access thereto from the outside or rear of the firebox.

In the form of the invention shown the header 32 has a generally rectangular exterior form and provision is made for connection of tubes thereto along the upper and lower sides and for this purpose opposed walls of the water chamber 33 at the upper and lower parts of the header may extend in a more or less diagonal direction, the sides 40 of the header being laterally directed toward the rear of the firebox, as best shown in Fig. 2. While I have herein referred to these surfaces as diagonal, it is obvious that this word is used in a somewhat generalized sense as the surfaces may be as a whole curvilinear but the direction of the curve at the critical point would be generally substantially diagonal to the general plane of the rear wall of the firebox. As clearly 45 shown in Figs. 2 and 3, the ends of the tubes 27^a may be curved so that they are presented normally, that is, perpendicularly, to the inner or front diagonal wall and may be entered through suitable openings therein and rolled and beaded in these openings. At the opposite wall, that is, the outer or exterior wall which is exposed at the rear of the boiler, provision is made for access to the 50 interior of the water chamber 33 and to the ends of these tubes and this is most conven-

iently effected by the provision of suitable plugs 37 in this wall directly opposite the ends of the tubes 27^a. As is clear from Figs. 2 and 3, direct access is thus provided through these plugs to the interiors of the tubes along a smooth curve and by removal of the plugs access is provided to the tubes for cleaning or to the ends of the tubes when it is desired to remove any for repair or replacement or to return any which have previously been removed. The rows of plugs 37 are exposed at the rear wall of the boiler away from the fire in a position convenient of access and are located exteriorly away from the opening 31 through the header.

I have described in detail the particular embodiment of my invention shown as an example thereof in the accompanying drawings. It will be understood that the particularity of this description has had for its purpose making amply clear the nature of that particular embodiment and that the construction may be widely varied from the form shown without departing from the spirit of the invention. The subject matter of invention exemplified by this particular embodiment which I claim as new and desire to secure by Letters Patent I shall express in the following claims. 95

I claim:

1. In a locomotive firebox comprising a crown chamber and a foundation chamber, a back wall comprising tubes curved to enter normally the walls of said chambers, a frame-like header defining an opening through said back wall and having opposed walls disposed substantially diagonally to the back wall as a whole, plugs in the outer of said walls and certain tubes extending from the chambers entered through the opposed wall whereby to provide direct access to the interior of said tubes from the exterior of the firebox. 100

2. In a locomotive firebox comprising a crown chamber and a foundation chamber, a back wall comprising tubes entering said chambers, a frame-like header comprising a single integral casting defining an opening through said back wall and having upper and lower portions presenting exposed surfaces at the exterior of the back wall substantially diagonal thereto and having opposed surfaces substantially parallel to the first on the fire side, plugs in the first of said surfaces and tubes entering through the second opposite the plugs. 110

3. In a locomotive firebox comprising a crown chamber and a foundation chamber, a back wall comprising tubes curved to enter normally the walls of said chambers, a frame-like header defining an opening through said back wall and having rearwardly directed upper and lower portions providing inner walls to receive tubes from 120

said chambers and opposed walls through which access may be obtained to the said tubes and which are exposed at the rear of the firebox exteriorly of said opening.

5 4. In a steam generator in combination with a series of substantially coplanar tubes a header disposed in said plane and having a portion provided with walls diagonal to said plane, tubes being entered through one 10 of the walls, the opposed wall having provision for access to the ends of said tubes at the interior of the header.

5 5. In a steam generator in combination with a series of tubes a header extending 15 longitudinally of said series and having a laterally directed portion presenting inner and outer walls substantially diagonal to

said tubes considered as a whole, the tubes entering the inner wall and said header having provision for access to the interior of 20 the tubes through said outer wall.

6. In a steam generator in combination with a series of tubes a frame-like header defining an opening transversely of the series of tubes, the ends of tubes adjacent the 25 header being bent and entering a wall thereof diagonally and plugs opposite the ends of said tubes exposed at one side of the series of tubes as a whole and disposed exteriorly of said opening. 30

In testimony whereof, I have signed my name to this specification. *

VINCENT L. JONES.
